UNITED STATES PATENT OFFICE.

DARIEN W. DODSON, OF DORRANCETON BOROUGH, PENNSYLVANIA.

MEANS FOR CONTROLLING HYDRAULIC RAMS.

Application filed May 23, 1921. Serial No. 473,351.

To all whom it may concern:

Be it known that I, DARIEN W. DODSON, a citizen of the United States, residing at Dorranceton Borough, in the county of Luzerne and State of Pennsylvania, have invented certain new and useful Improvements in Means for Controlling Hydraulic Rams; and I do hereby declare the following to be a full, clear, and exact description of the invention, such as will enable others skilled in the art to which it appertains to make and use the same.

This invention relates to hydraulic rams and more particularly to means, automatically actuated and controlled by a stream of water shunted through a conduit from the spring or other head of water whence the ram derives its impetus current through the drive pipe, for keeping the ram in continuous operation as long as the water supply in the spring, drive tank, or other reservoir is high enough to feed the shunt conduit.

In so far as I am aware the usual practice in the installation of rams heretofore has been to measure the flow, from the proposed source of water supply, in gallons per minute at time of normal supply, estimate the minimum flow, and install a ram that will operate normally and continually with the minimum flow. At time of measurement the water supply may be ample to keep a ram in operation; but drought may reduce the supply below the requirements of any ordinary ram. As a consequence of reduction of flow below the estimated minimum the ram ceases to operate. A trip to the ram is then necessary for the purpose of closing the impetus valve in order to allow the spring or reservoir to fill; then another trip to open the valve in order to start the ram, which then operates for a brief period and again "dies" or ceases to operate; whereupon the described operations have to be repeated. By reason of the failure of rams to continue in operation during periods of low water supply and the excessive annoyances due to the constant attention required to start and restart them, they have failed to come into the extensive use which the simplicity of the principle involved in their operation and the low cost of installation and maintenance in localities to which they are adapted would seem to justify.

It is the general purpose of my invention

to cause rams to continue in action without attention as long as there is any water flowing into the spring or other reservoir of supply.

In order to achieve the purpose of this invention I have devised means including a gravity motor controlled by a shunt flow from the source of supply to quickly drive the valve from its seat to start the ram; means actuated by the motor to wedge the valve against its seat automatically and hold it there pending an accumulation of drive water sufficient to again close it after it has been opened; an improved stop for limiting the advance of the means for holding the valve closed so that the said holding means will not obstruct the full movement of the valve under the impetus of the drive water; means to lift the stop free of the path of the valve stem in its movement; means to stop the intermittent operation of the motor, controlled by flow of water escaping through the port of the impetus valve; an adjustable housing or frame work for supporting the several means aforesaid, a shunt conduit comprising an improved siphon adapted to afford an even and steady flow of water for operating the motor, and various subcombinations and details of construction more fully pointed out in the ensuing description, defined in the appended claims and illustrated in the accompanying drawings.

In the drawings, in which like reference characters indicate like parts throughout the several views:

Figure 1 is an elevation of my improved ram controlling mechanism showing the impetus valve locked up in closed position and the motor ready to operate;

Figure 2 is an elevation of the same mechanism as that shown in Figure 1, but with the motor mechanism in the position assumed after it has operated to open the impetus valve;

Figure 3 is an elevation of the motor mechanism viewed from the right of Figure 1;

Figure 4 is an elevation of the motor mechanism viewed from the left of Figure 2;

Figure 5 is a section on the line 5—5 of Figure 3, viewed from the left;

Figure 6 is a section disclosing the same parts as are disclosed in Figure 5, but in the position assumed during the descent of the

gravity spill pan after it has caused the impetus valve to be unlocked and is causing said valve to descend.

Figure 7 is a vertical section on the line 5 7-7 of Figure 4 viewed from the right.

Figure 8 is a diagrammatic illustration of a drive tank or supply reservoir, drive pipe, shunt supply and ram with the improved control mechanism of this invention applied 10 thereto;

Figure 9 is a view of an improved siphon designed to afford a steady even flow from the reservoir to the shunt conduit;

Figure 10 is a bottom plan view of a leak 15 bucket for controlling the operation of a switch motor, and

Figure 11 is a section through the housing in the plane of the axes of clamping bolts 3.

20 In the drawings *a* is a conventional representation of a hydraulic ram; *b* a reservoir of water such as a drive tank adapted to receive flow from a spring; *c* a drive pipe conducting water from the reservoir to the 25 ram; *d* the mechanism for starting and continuing the operation of the ram when conditions have interfered with its normal operations; *e* the automatic switch for preventing operation of the starting and controlling mechanism *d* when the ram is operating normally; *f* the pipe through which water is delivered by the ram; and *g* the shunt pipe leading from the spring or drive tank for supplying water to actuate the 30 starting and controlling mechanism.

The casing of the impetus valve of the ram *a* is indicated at *a'*, the valve seat at *a²* and the impetus valve at *a³*, said valve being adapted, as well understood, alternately 40 to close in response to the pressure of water rushing from the drive pipe, and to open under the influence of gravity after the rush of water has been checked. The valve casing *a'* is open at both sides above the valve seat 45 to permit escape of water, and, in the embodiment shown, has two opposite risers *a⁴* supporting a centrally perforated bridge *a⁵*, from which a hollow guide stem *a⁶* projects upward centrally. The stem *a⁷* of impetus 50 valve *a³* is guided so as to slide freely in the guide *a⁶*. Rigid with the valve stem *a⁷* above the upper end of guide *a⁶* is a collar *a⁸* to limit the extent of downward or opening movement of the valve and to be engaged by 55 a latch or other locking member when the valve is closed, to temporarily hold said valve closed in periods when, as during periods of drought, the controlling mechanism comes automatically into operation. Above 60 the collar *a⁸* on the upper end of stem *a⁷* is a removable cap flange *a⁹* designed to be engaged by a device for striking the valve stem so as to forcibly unseat it at the proper time, as will be presently explained. A buffer washer *a¹⁰* surrounds the stem *a⁷*, rest-

ing normally on a supporting member connected to the housing to be later described, and cushions the fall of the valve by engaging the collar *a⁸*.

A housing, indicated as an entirety by the 70 numeral 1, is secured to the stem *a⁶* in such manner as to be adjustable vertically a limited extent. The base 2 of the housing has a half round vertical groove engaging the guide *a⁶*. Two bolts 3 project from the side 75 of the base 2, one on each side of the groove. At one side of the groove that fits the guide *a⁶* is a smaller half rounded threaded vertical groove for receiving an adjusting bolt. A cap member 4, provided with half round 80 vertical grooves corresponding with those in base 2 and with suitable holes for the bolts 3, is secured by nuts 3^a, so that the housing 1 may be mounted on the guide stem *a⁶*, but in such manner as to permit it to move up 85 or down thereon. An adjusting screw 5, threaded into the smaller vertical cavity between the base 2 and cap member 4, is adapted to be rotated so as to raise and lower the housing, the end of said screw 5 bearing 90 against the bridge *a⁵*. A screw 6 threaded through the cap 4 may be set up to secure the housing firmly to the guide *a⁶* of the impetus valve casing and prevent rotation thereof after the appropriate adjustment 95 has been made by the adjusting screw 5. Rising from the opposite side of the base member 2 are two lateral upright arms 7 and 8, the upper ends of which are tied together with a cross tie 9, preferably of brass 100 or bronze, the latter serving as a bearing member upon which the oscillatory actuator of a gravity motor mechanism is saddled so that it may vibrate with freedom between its limits of movement, which are fixed by a 105 stop 7^a at the end of a bracket 7^b secured to arm 7 of the frame, and a stop 8^a rigid with the inner side of arm 8 of the frame. Resting on the base 2 and cap 4 there may be a U shaped member 4^a if desired for supporting the washer *a¹⁰*.

The oscillatory actuator comprises a rocking lever frame 10, having a wide saddle bearing resting on the tie 9. The saddle bearing, at least, and preferably the lever 115 frame, as well as the tie rod 9 may be of brass, bronze, or other metal not subject to rust or corrosion. In the form illustrated the lever frame 10 has two spaced parallel arms 12 projecting at one side of the bearing 110 to support an actuator pan 13, adapted to tilt the lever frame downward when it is filled with water. Attached to the lever frame at the end opposite the pan 13 is a permanent weight 14, adapted to return the 120 frame and hold it in the position illustrated in Figs. 1, 3 and 5, when said pan is empty; and it will be understood that said weight 14 will hold the pan 13 elevated until it has 125 received water nearly to the level of its pour- 130

ing nozzle 13^a which is in communication with the interior of the pan by holes 13^b, owing to the advantage of position of said weight when the pan is elevated; whereas 5 the pan, after it has been dropped, will remain depressed until nearly all of the water has run out owing to its advantage of position when depressed. The end and sides of pan 13 nearest the bearing 11 are higher 10 than the remaining sides as shown at 13^c to permit a heavy charge of water to be received. Depending from the lever frame 10 is a stop and actuator arm 15 so disposed as to engage said stop lug 8^a and limit 15 the movement of the lever frame under the influence of weight 14, while the stop lug 7^a limits the movement of said frame when tilted by the water laden pan 13, by engaging a member attached to said frame to be 20 hereinafter described. When pan 13 is in the position illustrated in Figs. 1 and 3 and water is continually flowing from the nozzle 9^a of the shunt pipe 9, it is obvious that the lever frame 10 will intermittently oscillate dependent upon the rate of discharge from the nozzle 9^a, unless there are modifying conditions other than have thus far been described.

In addition to the parts thus far mentioned 30 the lever frame 10 is provided with a tie plate 16 connecting the outer ends of arms 12; a latch retracting arm 17; a bar 18 for engaging a latch stop lifter, a stud bearing 19 for the valve actuator trip, and 35 a stop surface 20 for limiting the releasing movement of said valve actuator trip, all to be hereinafter described.

When the actuator or gravity motor is functioning a spring actuated valve latch 21 40 engages beneath the collar a^s of the impetus valve every time the impetus valve is closed or elevated, said latch 21 having a latch head 22 with an abrupt tip for engaging the under side of said collar, and curved inclined face 45 23, adapted to be engaged by the edge of said collar when the valve rises in order to permit the rising valve to push the latch aside against the tension of its spring. Figs. 1, 3 and particularly Fig. 5 show the latch 50 21 holding the impetus valve closed. The latch 21 is forked at 24 and has on each prong a bearing lug 25 extending at substantially right angles to the body of the latch, the extremities of said lugs being 55 rounded and fitted to corresponding bearing cavities 26 in the base 2 of the housing, so disposed that the axis of movement of the latch intersects the valve stem a^t . Projecting outward and downward from said base 2 60 is a rod 27, having a threaded extremity 27^a, straddled by the fork of latch 21. Curved ended lugs 28, project from the prongs of the forked latch body shown, above and from the side opposite lugs 25, for the purpose of 65 receiving the pressure of a spring 29, tend-

ing to hold the latch in locking position when it has once been locked, or in unlocked position when it has been unlocked. An annular spring end plate 30 having ears 31 with rounded notches for receiving lugs 28 70 bears against said latch 21. A nut 32 having a handle 33 is threaded on the threaded end 27^a of rod 27. Both nut 32 and end plate 30 are provided with annular bosses serving as seats to confine the ends of the 75 coil spring 29, which surrounds the rod 28 and exerts its tension on the nut 32 and plate 30 and through the latter on latch 21. The relative positions of the spring, latch and associated parts is such that when the latch 80 21 is forced fully back away from locking position the line of force exerted by spring 29 passes slightly below the pivotal axis of said latch exerting sufficient pressure to retain the latch quiescent in unlocked position; 85 but when the latch is locked, the line of force of said spring passes well above the pivotal axis of the latch so that after the latch is moved a little toward locking position the spring snaps it with energy to such position. 90 As the latch head travels upward in an arc in moving to locking position, the head, engaging beneath the relatively wide collar exerts a camming action thereon, thereby powerfully forcing the impetus valve a^s into 95 engagement with its seat a^o . The tension of spring 29 may be varied by adjusting the nut 32 by means of the handle 33.

On one side of the latch head is a laterally projecting latch stop engaging lug 34 as 100 best shown in Figs. 2, 5 and 6. This latch stop lug 34 is for the purpose of engaging the shoulder 35 of a pivoted latch stop 36, in order to prevent the latch head 22 from moving so far inward when it is set to engage the collar a^s on its next upward movement that it will rest in the path of the cap a^o and present an extended surface to the pressure of the collar a^s during its upward movement, under the influence of the water 105 in the drive pipe. The said latch stop 36 is pivoted on a stud 37, preferably of brass or bronze, extending laterally from a bracket arm 7^c on the upright arm 7. The shoulder 35 when engaged over the lug 34 permits the 110 latch head 22 to advance under pressure of spring 29 far enough for its edge to engage the edge of collar a^s during its upward movement, be moved aside thereby, and to snap under said collar, but not far enough to 115 bring the inclined surface 23 of the latch head into the path of the cap a^o of the valve, or to present the entire inclined surface 23 to the rubbing friction of collar a^s . By this means the valve is not materially obstructed 120 should it rise while the latch is set and the pan 13 raised. In this condition the collar a^s on the rising valve, when near the upward limit of its movement, strikes the tip of latch 36, lifting the shoulder 35 free of the 125 130

lug 34, whereupon the latch head 22 springs inward into full engagement beneath the collar a^8 so that the full force of spring 29 is exerted to push the valve a^8 to its seat.

5 In order to release the latch 21 from engagement with the collar a^8 an arm 38 having a long laterally extending trip lug 39 is secured to the lug 34 on the latch. The trip lug 39 rests in the path of arm 17 10 depending from the lever frame 10, the result being that when the lever frame 10 tilts, by reason of the weight of water in the pan 13, the latch will be carried back and held back by the spring 29, until the arm 15 15 restores it by striking the lug 39 on the other side when the lever frame 10 is restored to its initial position by the weight 14 after pan 13 has been emptied. Said lug 39 lies in the path of arm 15 for the 20 purpose of initiating the movement of latch 21 toward locking position.

In order to lift the latch stop 36 clear of the path of the collar a^8 , thus affording the valve an absolutely unobstructed path closing movement thereof after the latch 21 has released it, or when the actuator is held out 25 of operation the said latch stop is lifted by the frame 10 during the downward movement of pan 13. For this purpose a hook 30 40 is pivoted at 41 to the latch stop 36 between its ends, the hooked end 42 of said pivoted hook resting always in position to engage over the bar 18 near the end of the upward movement of that end of the frame 35 36 that supports weight 14. Figure 2 indicates in dotted lines the elevated position of the latch stop when lifted by the tilting of frame 10 due to the weight of water in pan 13.

40 In order to push the impetus valve from its seat after it has been released by retraction of the latch 21, as before described, a powerful and quick acting lever 43 of the first order is caused to press smartly upon 45 the cap a^9 on the end of the valve stem with a camming action to unseat the valve. Motion is given to this lever by a lost motion connection with the tilting of frame 10 when it is tilted by the full pan 13. The said 50 lever 43 is pivoted on a stud 44, preferably of brass or bronze, projecting from the inner side of frame upright 7 just beneath and a trifle at one side of the saddle bearing or tie rod 9. Lever 43 is prevented from lateral displacement by guide 7 a on bracket 7 a . The short arm 45 of the lever 43 is disposed 55 above the cap a^9 of valve stem a^7 . When the pan 13 is elevated and empty as shown in Figs. 1, 3 and 5, the said short arm rests 60 a short distance above said cap a^9 , by reason of a lug 43 a on one side of the long arm engaging bracket 7 a , the short arm being overbalanced by the weight of the longer arm. The longer arm of lever 43 terminates in a 65 shouldered end 46, adapted to be caught by

the lateral hooked end 47 of a lifting and tripping member 48 pivoted to the lever frame 10 on stud 19. The said lifting and tripping member is over weighted at 50 so that its hooked end tends to swing to position to engage the shoulder 46 on the valve pushing lever 43; the lower face of the end 47 is beveled and the curved guard 46 a on the lever 43, engaging said end 47 prevents the member 48 from swinging in above the 75 tail end of the lever 43, and the end of bracket 7 prevents it from swinging inward too far when the end 47 has passed below the shoulder 46. The member 48, having, as stated a tendency to swing so as to bring the end 47 under the shoulder of valve unseating lever 43, when frame 10 tilts under the influence of a full pan, the hook 47 engages with the shoulder 46 after the frame 10 has attained a great momentum thus 80 snapping the end 45 of lever 43 downward upon the valve stem, with a camming blow and driving the valve surely from its seat. Before the pan 13 has carried the frame 10 to the limit of its tilting movement a trip 90 finger 51 on lifting and tripping member 48 comes into contact with the stop lug 7 a as indicated in Fig. 6. Continued movement of the frame 10 causes the release of hook 47 from shoulder 46, throws the hook 95 end 47 clear of lever 43, and presses the trip finger 51 down against the stop surface 20, before mentioned, on frame 10. Contact of trip finger 51 with stop lug 7 a also limits the descent of that end of the frame which 100 supports the pan 13. In this position the pan is gradually emptied through the spout 13 a , after which, as before stated, the weight 14 vibrates said frame in the opposite direction to the normal starting position. 105

The mechanism thus far described would continue intermittently to operate, in the manner set forth in conjunction with the description of the mechanism, whether the supply of water flowing in the drive pipe 110 were meager or abundant. In order to prevent the continued oscillation of the said gravity actuating mechanism when the water supply is abundant and the ram is, therefore, operating normally, a device 115 which I here designate an automatic motor switch is applied. This switch causes cessation of the oscillation of the motor mechanism when the supply is so abundant that the ram operates normally, and permits the 120 oscillation to start again should the normal operation of the ram cease, by reason of insufficient water, sticking of the impetus valve, or failure of the valve to operate normally for other causes. 125

The said switch is in the nature of an auxiliary oscillatory weight motor carrying a spout adapted to be oscillated to and from a position beneath the shunt pipe nozzle 9 a , and which, when in position beneath said 130

nozzle, directs the water therefrom into the pan 13, thus keeping frame 10 in the position illustrated in Fig. 2, with every part above the valve clear of its range of movement.

Projecting from the base 2 of housing 1 at the lower end of frame arm 8 is a knife bearing 52. Above said knife bearing and projecting from said frame arm 8 is a stop 10 lug 53 notched on opposite sides, and guides 54. Saddled on the knife bearing is an oscillatory weight motor frame, consisting of a three armed lever, one arm 55, carrying a permanent weight 56, another arm 57 15 having a hooked end 58 adapted to suspend a leak bucket 59 having a hole 60 in its bottom, which may be opened more or less or closed by a gate 61. Arms 55 and 57 extend downward at an angle to each other 20 forming a saddle bearing at their junction which rests upon the knife edge bearing 52. The third arm 62 of said three armed lever projects upward and is formed with a downward projecting lug 63 spaced from 25 the body of the arm 62. Said stop lug 53 projects into the space between lugs 63 and arm 62, thus serving to limit the arc of oscillation of the motor switch. The guide surfaces 54, and lateral notches in opposite 30 faces of lug 53 serve to steady the lever arm 62, to which is secured the long continuation 64 carrying on its upper extremity the spout 65 before referred to.

The movements of this switch motor are 35 controlled by water escaping past the impetus valve. In order to utilize this flow a trough is placed so as to catch escape water and direct it into the bucket 59. For this purpose two lugs 66 and 67 project from the frame cap 4, and trough 68 is 40 hung therein in an inclined position by hooked straps 69 and 70, so that a portion of the water escaping past the impetus valve will be directed into bucket 59. As 45 long as the valve is opening and closing normally by reason of ample flow in the drive pipe, the bucket 59 will overbalance weight 56, thus holding the switch trough 65 beneath the shunt pipe nozzle g^1 in position 50 to direct the flow into pan 13, thus keeping said pan down. Should the impetus valve close and remain closed, bucket 59 would soon be emptied through the opening 60, whereupon the permanent weight would 55 swing the switch spout 65 from beneath the shunt pipe nozzle g^1 . The flow from shunt pipe then descends between said switch spout 65 and the pan 13, the pan 13 empties, starting the ram controlling weight 60 motor again into operation.

In order to cause an even flow through the shunt pipe g , whatever may be the level of water in the spring or drive tank b , I affix a siphon g^2 to the inlet end of said 65 shunt pipe. The connection between the

siphon and the shunt pipe is made by a pipe section g^3 of a diameter less than that of the pipe g or the rest of the siphon and said reduced section g^3 is preferably of brass, bronze, or other non-corrosive material 70 which will not rust and clog, but remains constantly of the same capacity. By this means the siphon starts easily and a constant even delivery of water to the control motor may be had as long as there is sufficient head in the spring or drive tank to operate the ram. Should the water fall so low as to stop the operations of the ram entirely, as when it falls so as to admit air to the siphon, the operation of the ram will 75 cease until the water accumulates in the spring or drive tank, over the bend of the siphon, whereupon the motor will resume operations, start the ram and keep it going until the head is again depleted as described. 80

By means of the described controlling mechanism a ram may be kept in operation without attention as long as there is any water flowing, although the delivery of the ram may, of course, be at a lower rate in 90 times of drought.

Owing to the fact that the lever frame 10 is saddled upon the rod 9 and the switch frame rests upon knife bearing 52, both may be lifted bodily from their bearings 95 and taken off. These bearings cannot clog the operation of the mechanism. All stud bearings for moving parts are of brass, bronze, or other non-corrosive metal, as are also, preferably, the various movable 100 latches, stops and stop lift devices, substantially unaffected in their operation by exposure to moisture.

While I have illustrated and described my invention in the best embodiment now 105 known to me, it is to be understood that changes in form and details of structure without substantial changes in principle or mode of operation may be made without departing from the spirit of my invention. 110

What I claim and desire to secure by Letters Patent is:

1. In mechanism of the class described, the combination of an impetus valve, with a latch adapted to engage said valve and hold it closed, and automatically controlled means operating periodically to release said latch.

2. In mechanism of the class described, the combination of an impetus valve, with 120 a latch adapted to engage said valve and hold it closed, and a water motor operating to release said latch periodically.

3. In mechanism of the class described, the combination of an impetus valve, with 125 a latch adapted to engage said valve and hold it closed, an oscillatory motor operated to release said latch periodically, said motor comprising a lever frame having a counter weight at one side of its bearing and an 130

actuator pan at the other side thereof, said actuator pan being constructed to discharge its contents when depressed.

4. In mechanism of the class described, 5 the combination of an impetus valve, with a latch adapted to engage said valve and hold it closed, an oscillatory motor comprising a lever frame having a counter weight at one side of its bearing and an actuator 10 pan at the other constructed to discharge its contents when depressed and an arm depending from said lever frame adapted to release the valve when the lever frame moves in response to the weight of water 15 in the pan.

5. In mechanism of the class described, the combination of an impetus valve, with a latch adapted to engage said valve and hold it closed, an oscillatory motor comprising a lever frame having a counter weight at one side of its bearing and an actuator 20 pan at the other side thereof, said actuator pan being constructed to discharge its contents only when depressed, a pair of spaced 25 arms depending from the lever frame, a projection on said latch adapted to be engaged by one of said arms when the lever frame tilts in one direction and by the other of said arms when the lever frame tilts in the 30 opposite direction.

6. In mechanism of the class described, the combination of an impetus valve having a collar, with a latch adapted to engage under said collar and hold said valve closed, 35 said latch having an inclined face adapted to be engaged by the collar in the upward movement of said valve toward its seat, means adapted and arranged to urge said latch yieldingly toward locking position, 40 a movable stop for limiting the extent of movement of said latch to engaging position beneath said collar, said stop having a part adapted to be engaged by the upper side of said collar and released from engagement with the latch by the upward 45 closing movement of the valve.

7. In mechanism of the class described, the combination of an impetus valve having a collar, a latch adapted to engage said collar and hold the valve closed, means for 50 yieldingly urging said latch toward locking position, a movable stop adapted to engage said latch and limit its movement toward locking position, a motor and connections 55 adapted to periodically release said latch and simultaneously elevate said stop out of the path of the valve stem in its closing movements.

8. In mechanism of the class described, 60 the combination of an impetus valve having a collar, a latch having a tendency and adapted to engage said collar and hold the valve closed, an oscillatory gravity water motor operating periodically to release said 65 latch, a movable stop adapted to limit the

extent of movement of said latch toward its locking position and means actuated by a movement of the motor caused by a charge of water for lifting said stop when the valve is retracted.

70

9. In mechanism of the class described, the combination of an impetus valve having a collar, a latch having a tendency and adapted to engage under said collar and temporarily hold said valve to its seat, an oscillatory gravity water motor comprising a lever frame having a counter weight at 75 one side of its bearing and an actuator pan at the other, a movable stop adapted to limit the movement of the latch toward locking 80 position, said stop having a part projecting above said collar, a lost motion connection between said stop and said lever frame, whereby said stop will be lifted by the lever frame near the end of the movement there- 85 of caused by the descent of the pan.

10. In mechanism of the class described, the combination of an impetus valve having a collar, with a latch adapted to engage beneath said collar and hold the valve closed, 90 a pivoted stop for limiting the movement of the valve toward locking position, said stop having a portion projecting over the collar, an oscillatory gravity water motor comprising a lever frame having a weight at one side 95 of its bearing and an actuator pan at the other, a link pivoted at one end to said stop and having a hook at its other end, and means on the counter weighted end of the lever frame for engaging said hook near the 100 end of the movement of the frame caused by the descent of the pan.

11. In mechanism of the class described, the combination of an impetus valve, a pivoted lever having one end adjacent but 105 spaced from said valve when the latter is closed, and a motor adapted periodically to move said lever so as to effect a camming blow on said valve to force it from its seat.

12. In mechanism of the class described, 110 an impetus valve, a housing, a motor comprising an oscillatory frame, a lever for unseating said valve, and a lost motion connection between said frame and said lever for operating the lever by impact due to movement of the frame.

13. In mechanism of the class described, the combination of an impetus valve, a pivoted lever having its end normally spaced above the end of the stem of said valve, a 120 motor comprising an oscillatory frame, a movable device on said frame adapted to engage and operate said lever and means to trip said device and release the lever after the latter has unseated the valve.

125

14. In mechanism of the class described, the combination of an impetus valve, a housing, a counter weighted lever pivoted on the housing and normally resting with one end above the end of the valve stem, a motor 130

comprising an oscillatory frame mounted on said housing, a lever operating device pivoted on said frame in position to engage said lever and operate it during the movement of the frame in one direction, and means for tripping said device and releasing the lever after it has unseated the valve.

15. In mechanism of the class described, the combination of an impetus valve, a housing, a counter weighted lever pivoted on said housing, having one end normally spaced above the end of the valve stem, an oscillatory motor comprising a lever frame mounted on said housing, a lever operating member pivoted to said frame and adapted to engage said counter weighted lever, said lever operating member comprising a bell crank having on one arm a hooked depending end adapted to engage the valve operating lever during the latter portion of a tilting movement of said frame, and a stop on the housing arranged to engage the other arm of said bell crank for releasing said valve actuating lever after the valve has been unseated.

16. In mechanism of the class described, the combination of an impetus valve, a latch adapted to hold the valve closed, a motor, a lever having one end resting normally adjacent the valve, and means controlled by the motor for releasing the latch and operating the lever to unseat the valve.

17. In mechanism of the class described, an impetus valve having a latch engaging surface, a latch having a head adapted to engage said surface with a camming effect to force said valve against its seat, and a motor for controlling said latch.

18. In mechanism of the class described, an impetus valve having a latch engaging surface, a pivoted latch having a head for engaging said surface to force said valve toward its seat and hold it seated, and means adapted and arranged to move said latch head in an arc against said surface so as to wedge the valve against its seat.

19. In mechanism of the class described, the combination of an impetus valve having a collar, a latch comprising a body and a head adapted to engage under the collar, said latch body being pivoted on the housing on an axis substantially intersecting the axis of the valve stem and a spring arranged to exert its pressure on said latch to force it toward locking position.

20. In mechanism of the class described, an impetus valve, a pivoted latch adapted to engage said valve and hold it seated, a spring bearing against said latch, said spring being so disposed as to exert its pressure lightly to hold said latch retracted, but to force said latch powerfully toward locking position after initial movement of the latch from retracted position, and a motor mecha-

nism for retracting the latch and initiating its locking movement.

21. In mechanism of the class described, the combination of an impetus valve having a collar on its stem, a latch adapted to engage under said collar when the valve is seated, said latch comprising a head, an elongated body having bearing lugs extending at right angles from its lower end, notched bearings for said bearing lugs, the axis whereof intersect the axis of said valve, a coil spring bearing against said latch on the side opposite said lug and arranged to exert its pressure along a line passing slightly below said bearing when the latch is retracted and along a line well above said bearing when the latch is in locking position.

22. In mechanism of the class described, the combination of an impetus valve, with a latch adapted to engage said valve and hold it in closed position, said latch comprising a body having a latch head and bearing lugs extending at right angles therefrom at the end opposite said head, bearing notches at opposite sides of the axis of said valve, lugs on the side of the latch body opposite and above said bearing lugs, a bearing plate engaging said lugs, a rod, a spring bearing head thereon, a coiled spring between the said bearing head and said bearing plate, the arrangement being such that when the latch is fully retracted the line of force of the spring extends slightly below said bearing notches and when the latch is in locking position the line of force extends well above said bearing notches.

23. In mechanism of the class described, the combination of an impetus valve having a collar on its stem, a latch comprising a body and a head adapted to engage under said collar when said valve is seated, said latch body being pivoted on an axis substantially intersecting the axis of the valve, a spring arranged to hold said latch in retracted position and to force said latch into locking position when moved slightly from its retracted position, a motor comprising an oscillatory frame and means on the said frame for retracting the latch when the frame moves in one direction and for initiating the locking movement of the latch when it moves in the other direction.

24. In mechanism of the class described, the combination of an impetus valve, a housing comprising spaced uprights, a transverse bearing member between said uprights, an oscillatory frame having a saddle bearing resting on said bearing member, means on said oscillatory frame for controlling the position of said impetus valve and stops on the housing for limiting the oscillation of said frame in both directions.

25. In mechanism of the class described,

- the combination of an impetus valve, means for controlling the position of said valve comprising an oscillatory motor having a counter weight on one side of its bearing 5 and an actuator pan on the other side, a conduit arranged to deliver a stream of water into said pan when said pan is elevated and to discharge at one side of said pan when it is depressed, a switch spout 10 adapted to be moved from a position at one side of said delivery spout to a position beneath said delivery end so as to direct the flow into the pan when the latter is depressed, and a leak bucket adapted to receive 15 waste water from said valve for controlling the position of said spout.
26. In mechanism of the class described, the combination of an impetus valve, a housing, an oscillatory motor for controlling 20 said valve, said motor comprising a lever frame having a counter weight on one side of its bearing and an actuator pan at the other side thereof, a conduit for delivering water into said pan when in its elevated position, a counter weighted auxiliary oscillatory motor pivoted on said frame, a switch spout operated thereby, a leak bucket adapted 25 to operate said auxiliary motor, said bucket being disposed so as to receive waste 30 water flowing from said impetus valve, and means for limiting the oscillations of said auxiliary motor so as to move the spout beneath the delivery end of the conduit when said bucket is filled with water and to re- 35 move the switch spout from beneath said delivery end when said bucket empties.
27. In mechanism of the class described, the combination of an impetus valve, a housing, an oscillatory motor mounted on said 40 housing, comprising an actuator pan, a conduit for delivering to said pan when in its elevated position, a knife bearing on said housing, a counter weighted oscillatory frame mounted on said knife bearing, a 45 switch spout carried on said oscillatory frame, means for limiting the oscillations of said frame so that said spout may move from a position at one side of the delivery end of said conduit to a position beneath 50 said delivery end, a leak bucket for controlling said oscillatory frame, and means for directing water flowing from the impetus valve into said bucket.
28. In mechanism of the class described, 55 comprising an automatic switch controlled by water flowing through the impetus valve,
- a spout, and means for detachably securing said spout in position to receive water from the impetus valve and direct it so as to operate the switch. 60
29. In mechanism of the class described, an impetus valve, a water motor, a conduit for delivering water from the reservoir to said motor and a siphon in said reservoir connected to said conduit. 65
30. In mechanism of the class described, an impetus valve, a water motor for controlling said valve, a conduit for delivering water to said motor, a siphon connected to the inflow end of said conduit in the reservoir, and a reduced section connecting one arm of said siphon to the conduit. 70
31. In mechanism of the class described, an oscillatory gravity motor comprising a counter weighted frame carrying an actuator pan, means for limiting the amplitude of the oscillations of said frame, said pan having a spout at its discharge end the bottom of which extends at an oblique angle from the bottom of the pan, and is substantially horizontal when the frame is at the limit of the movement caused by the weighted pan, said spout communicating with the interior of the pan by a hole in the wall of the latter. 75
32. In mechanism of the class described, an oscillatory gravity motor comprising a counter weighted frame carrying an actuator pan, means for limiting the amplitude of the oscillations of said frame, said pan having walls of greater depth at the end nearest the bearing of said frame than at the outer end, a spout at the outer end of said pan the bottom of which inclines upward from the bottom of the pan at such an angle that it is substantially horizontal 80 when the pan is at the limit of its discharging position, said spout communicating with said pan by a hole in the wall of the latter. 85
33. In mechanism of the class described, an oscillatory gravity motor comprising a counter weighted frame carrying an actuator pan, means for limiting the amplitude of the oscillations of said frame, said pan having a discharge outlet in the end farthest 90 from the frame, the frame being so disposed that substantially all water will be discharged from the pan only when the pan is fully depressed. 95
